UNITED STATES PATENT OFFICE

CHESTER I. HALL, OF PHILADELPHIA, PENNSYLVANIA, ASSIGNOR TO GENERAL ELECTRIC COMPANY, A CORPORATION OF NEW YORK

DESIGN FOR A ROOM THERMOSTAT

Application filed October 8, 1929. Serial No. 32,979. Term of patent 14 years.

To all whom it may concern:

Be it known that I, CHESTER I. HALL, a citizen of the United States, residing at Philadelphia, in the county of Philadelphia, State of Pennsylvania, have invented a new, original, and ornamental Design for Room Thermostats, of which the following is a specification, reference being had to the accompanying drawing, forming a part thereof.

The single figure of the drawing is a perspective view of a room thermostat embodying my new design.

I claim:

The ornamental design for a room thermostat substantially as shown.

In witness whereof, I have hereunto set my hand this 4th day of October, 1929.

CHESTER I. HALL.
